DESIGN FOR A BATTERY TESTER

Egmont Arens, New York, N. Y., assignor to Atlas Supply Company, Newark, N. J., a corporation of Delaware

Application November 25, 1938, Serial No. 81,352

Term of patent 7 years

To all whom it may concern:

Be it known that I, Egmont Arens, a citizen of the United States, residing at New York, in the county of New York and State of New York, have invented a new, original, and ornamental Design for Battery Testers, of which the following is a specification, reference being had to the accompanying drawing, forming part thereof.

In the drawing:

Fig. 1 is a front elevation of a battery tester showing my new design.

Fig. 2 is a rear elevation of the same.

Fig. 3 is a top plan view, and

Fig. 4 is a side elevation of said battery tester showing my new design.

I claim:

The ornamental design for a battery tester, as shown.

EGMONT ARENS.
